UNITED STATES PATENT OFFICE.

JOHN N. KAILOR, OF NEWARK, ASSIGNOR TO THE NEWARK MACHINE COMPANY, OF COLUMBUS, OHIO.

RUBBER FOR CLOVER-HULLERS.

SPECIFICATION forming part of Letters Patent No. 310,521, dated January 6, 1885.

Application filed August 27, 1884. (No model.)

To all whom it may concern:

Be it known that I, JOHN N. KAILOR, a citizen of the United States, residing at Newark, in the county of Licking and State of Ohio, 5 have invented certain new and useful Improvements in Rubbers for Clover-Hullers, of which the following is a specification, reference being had therein to the accompanying drawings.

10 My invention relates to an improved metallic rubber or tooth for the cylinders of clover-hullers; and the novelty consists in the peculiar construction and adaptation of the same, as will be more fully hereinafter set forth, and pointed out in the claims.

15 The invention is designed as an improvement upon the rubber patented March 6, 1877, No. 188,064, the title to which patent and to this invention resides in the same party. The 20 device set forth in that patent had corrugated sides, a thick back, and a smooth front. The sides were in a plane between the front and back, and were consequently at an angle to each other, and the corrugations were so arranged as to operate laterally upon the pods and heads of the clover, the said material being rubbed more thoroughly at the rear portions of the rubber. The corrugations extended in a plane from one edge to the other 25 in the form of straight grooves, and the front or rear edges were flat or slightly rounding and smooth. Subsequent experiments have developed that such rubbers did not combine all the valuable advantages necessary, and 30 that some of the features were faulty.

35 My improved rubber is adapted for service with most complete results upon the lower cylinder of a clover-huller of the class described in the patent hereinbefore mentioned, 40 and the essential object of the invention is to produce a rubber having a thin narrow front edge, with some of the corrugations extending thereto, and parallel corrugated sides. The sharp front is produced by a gradual incline 45 commencing near the front both of the body and the corrugations, and allows the rubber to enter the material easily and gradually without pushing the heads and pods along in front of the rubber, and also provides a multiplicity of breaking-edges at the junctions of 50 the corrugations with the front edge. This

feature of readily entering the material gives a gradual and sufficient feed between the moving rubbers and those of the concaves, to effect a very complete breaking up of the hulls and 55 pods, and upon this feature, with the multiplied projecting edges on the front and the vertical sharp edge, rests the gist of the invention.

The invention is illustrated in the accompanying drawings, which form a part of this specification, and in which—

Figure 1 is a side elevation of my improved rubber. Fig. 2 is a front elevation, and Fig. 3 is a horizontal section taken through the 65 line *xx* of Fig. 1. Fig. 4 is an enlarged detail.

Referring to the drawings, A designates the shank of my improved rubber, which is rectangular in cross-section, to correspond with a 70 bearing in the cylinder having a similar form, and which serves to prevent the rubber from displacement. The shank A is threaded at *a* to receive a securing-nut, *a'*, as is usual in such devices. The body of the rubber has two 75 parallel sides, and is of square or rectangular contour. The sides B have corrugations or ridges *b*, and these corrugations lie obliquely or transversely to the line of travel, or approximately so. Both the body and corrugations are chamfered off or inclined inward at *b'* to provide a sharp edge, C, the corrugations extending fully up to this edge C and forming a junction therewith. Where each 80 of the corrugations connects with the prow or edge C there are formed four projections, as seen in Fig. 4 at 1 2 3 4, which serve very efficiently to stir, break, separate, and disrupt the heads and pods of the clover.

85 This rubber is made of steel, and may be 90 used with success upon either cylinder or in either concave. The tap and nut are not essential, as the rubbers may be driven into closed cylinders or concaves which have been prepared for them. By omitting the prow C 95 and extending the grooves and ridges alternately up a vertical front edge, I can produce an undulated contour upon a sharp front; but this feature is made the subject-matter for a separate application filed simultaneously 100 herewith.

In lieu of making the ridges or corruga-

tions on opposite sides of the rubbers meet at the same point on the prow, they can break joints or alternate from side to side of the prow, as will be readily understood.

5 I have hereinbefore shown and described the rubber as having parallel sides; but I do not wish to be understood as limiting myself to rubbers in which the sides are geometrically parallel, or substantially so, since my improved construction can be employed on rubbers the sides of which are not parallel.

Having thus fully described my invention, what I claim, and desire to secure by Letters Patent of the United States, is—

15 1. A rubber for clover-hullers, comprising two sides having corrugations arranged transverse to the line of travel, a chamfered or inclined portion, as b' , forming a sharp front edge, C, and multiplied projections 1 2 3 4, as 20 set forth.

2. A rubber for clover-hullers of the class described, comprising, essentially, two parallel sides having corrugations arranged transverse to the line of travel, a chamfered or inclined portion, as b' , to give a sharp front edge, C, 25 and multiplied projections, as 1 2 3 4, as set forth.

3. The rubber described, having the parallel corrugated sides B b, sharp front b' , forming a ridge or prow, C, projections 1 2 3 4, the 30 rectangular shank A, having thread a , and nut a' , the whole adapted to serve as and for the purposes set forth.

In testimony whereof I affix my signature in presence of two witnesses.

JOHN N. KAILOR.
